WINDOW SHADE AND CURTAIN FIXTURE

Chester C. Doty, Dunkirk, N. Y.

Application October 27, 1947, Serial No. 782,361

10 Claims. (Cl. 248—252)

1

This invention relates generally to window fixtures of the type designed to support roller shades, curtains and other draperies.

A principal object of the present invention is to provide a fixture of the character stated wherein the use of bolts and screws for securing together adjustably connected parts of the fixture, is done away with, the said adjustably connected parts being joined in a novel interlocking manner whereby desired adjustments may be made easily and quickly and at the same time a strong, firm and durable construction is had.

Another object of the invention is to provide a window fixture wherein a novel coupling is provided between a base plate which is permanently secured to the window frame and a forwardly projecting arm, by means of which the arm may be removed and replaced easily and quickly without the employment of securing elements other than a frictional binding means forming a part of the supporting base plate.

Still another object of the invention is to provide in a window fixture of the character stated, a novel connecting support between the ends of a shade roller and adjacent forwardly extending arms.

Still another object of the invention is to provide in a wall fixture of the character stated, a novel pole support and a novel means detachably coupling the pole support with the forwardly extending wall attached arm.

A still further object of the invention is to provide in a window fixture of the character stated, an extensible wall attached arm wherein a novel means is employed for securing the two relatively movable parts of said arm together after the desired adjustment has been made for lengthening or shortening the arm, without the employment of screws or other securing devices.

Other objects and advantages of the invention will become apparent as the description of the same proceeds and the invention will be best understood from a consideration of the following detailed description taken in connection with the accompanying drawing forming a part of the specification, with the understanding, however, that the invention is not to be limited to the exact details of construction shown and described since obvious modifications will occur to a person skilled in the art.

In the drawing:

Figure 1 is a view in perspective of a window shade and curtain fixture constructed in accordance with the present invention;

2

Figure 2 is a view in transverse section through the bracket arm and shade roller support.

Figure 3 is a view in perspective of the base plate.

Figure 4 is a view in perspective of the stationary arm part.

Figure 5 is a view in perspective of the inner end of the shiftable arm part.

Figure 6 is a view in elevation, with parts broken away, of the inner or rear side of the extensible curtain rod.

Figure 7 is a view in perspective of the lower part of a drape supporting saddle.

Referring now more particularly to the drawing the numeral 10 generally designates a window fixture or bracket constructed in accordance with the present invention which, in association with a similar bracket, forms a cooperating pair for mounting upon the frame of a window or door, 10 such frame being generally designated 11.

The bracket fixture 10 comprises the base plate 12 which is designed to be secured against the face of the frame 11 by screws 13. This base plate has a central opening 14 and above and below this central opening are parallel openings 15 formed by pressing out a portion of the metal, which pressed out portion of the metal is angled to form a guide 16. These guides 16 have their open sides directed toward one another as shown 25 for the reception of a portion of the hereinafter described bracket arm. As shown the formation of the openings 14 and 15 provides adjacent to 30 each guide, a relatively narrow strip of material which is designated 17. Each of these strips 17 are outwardly or forwardly bowed to provide a 35 friction spring for the purpose hereinafter stated.

Detachable connected with the fixed or base plate 12 is a forwardly extending arm unit which is generally designated 19. This arm unit is made 40 up of the two parts 20 and 21. Both of these parts 20 and 21 are in the form of a relatively long straight strip of material, the part 20, which will be referred to as the stationary part being slightly wider than the part 21 which will be referred to 45 as the shiftable part.

The stationary part 20 of the arm at one end has formed integral therewith, the foot plate 22 which is of slightly greater width in the vertical direction than the part 20 so that it projects 50 slightly at its top and bottom edges beyond the top and bottom edges of the stationary part 20. The foot plate 22 is adapted to be disposed against the front face of the fixed plate 12, the projecting top and bottom portions of the foot plate being slidably engaged in the guides 16.

The vertical width of the stationary part 20 is substantially equal to the distance between the opposing edges of the guides 16 as shown and it will be readily apparent that when the foot plate 22 is in mounted position upon the plate 12, compressive force will be applied to the spring holders 17 whereby to tightly bind the foot plate in the guides to prevent accidental movement of the bracket arm.

At the opposite end of the stationary part 20 from the foot plate 22, the part 20 is bent to provide the inwardly directed flange 23. This flange has formed therein the vertical slot 24 which is of the proper length to slidably receive the shiftable part 21.

Adjacent to the flange 23 the stationary part 20 is provided in its top edge with the slot 25 which cooperates with correspondingly formed slots 26 cut into the top edge of the shiftable part 21, for the purpose hereinafter set forth.

In order to hold the shiftable part 21 in any one of the several positions to which it may be adjusted with respect to the part 20, whereby a selected one of the slots 26 is maintained by the side of and in cooperative relation with the slot 25, the bottom edge of the shiftable part 21 is provided with the notches 27 which engage over the bottom edge of the slot 24. It will, of course, be understood that the slot 24 must be of a length slightly greater than the vertical width of the shiftable part 21 to permit such part to be lifted in order to disengage the notch 27 from the lower edge of the slot 24 when an adjustment of the two parts of the arm is called for.

The inner or back end of the shiftable part 21 of the arm is maintained against up and down movement, without hindering the longitudinal movement of the part 21 for the making of the several required adjustments, by the provision of a slot 28 which is formed longitudinally in the stationary part 20 and which is enlarged at its inner end as indicated at 29, and a T-shaped head or key 30 which is formed at the inner end of and projects laterally from the side of the shiftable part 21. This key 30 has the reduced neck portion 31 which engages in the guide slot 28 after the head of the key is passed through the enlarged open end 29 of the slot 28.

Positioned forwardly from the foot plate 22, the stationary part of the adjustable arm carries at its top and bottom edges, the upwardly and downwardly directed lugs 32. These lugs provide a means for detachably securing to the bracket arm an auxiliary bracket, which is generally designated 33, for connecting an end of a shade roller, to the bracket arm.

The auxiliary shade roller supporting bracket 33 is formed from a single strip of material which is bent transversely on two spaced parallel lines to form the divergent legs 34 connected by the straight intermediate portion 35 in which is formed an opening 36. This opening for one auxiliary bracket will be rectangular as shown to receive the squared gudgeon at one end of a curtain shade roller while the corresponding and cooperating auxiliary bracket will be provided with a circular opening for the round gudgeon at the other end of the shade roller. However, use may be made of two brackets having the rectangular opening here shown as the round gudgeon can rest in such an opening and function as efficiently as in a circular opening.

The auxiliary bracket 33 is mounted upon the

stationary part 20 by the extensible arm by spreading the legs 34 so as to receive between them the oppositely positioned lugs 32 and each leg 34 adjacent to its free end is provided with an aperture 37 for the reception of a lug, in the manner illustrated.

For the support of curtains between a pair of the arms 19 use is made of the two-part extensible rod which is generally designated 38 and which comprises the two angle strips 39 and 40 which are disposed in side by side relation. One of the strips, here shown as the strip 40, has at the opposite longitudinal edge from the right angularly extending flange 40', the inturned guide strip 41 in which the longitudinal edge of the other strip, here shown as the strip 39, slidably engages with the flange portion 39' of this other strip slidably engaged under the flange portion 40'. The remote ends of the strips 39 and 40 have the transversely directed slots 42 formed therein from the edges opposite the flanges. This curtain bar 38 performs the double function of providing a support for a curtain such, for example, as a lace curtain, and a connecting and 25 bracing means between the outer ends of a pair of the arms 19. When disposed between a pair of the arms an end of the bar portion is inserted into two adjacent slots 25 and 26 and the slot 42 receives the lower halves of the arm parts 20 and 21.

For the support of a curtain pole and/or draperies, at the outer ends of a pair of the extensible arms 19, there are provided two saddle units of the character here illustrated and generally designated 43. Such saddle unit is preferably formed of a single strip of metal of suitable character by bending the strip intermediate its ends to form a tongue part 44 of an over-all length substantially equal to the vertical width of the shiftable arm part 21. This tongue part comprises two thicknesses of the strip of material and is provided from its bottom edge with the vertical slot 45 which extends substantially half the height of the tongue. 45 The outer end of the extensible arm part 21 is provided with a relatively wide slot 46 from its top edge downwardly so that the upper part of the tongue 44 will be received in the slot 46 and the slot 45 will receive the lower half of the part 50 21 below the slot 46.

Above the tongue portion 44, the two sides are curved outwardly and upwardly as indicated at 47 and cooperate to form a substantially semi-circular space in which may be received an end 55 of a curtain pole. These two side portions 47 continue into the second upwardly and outwardly curving parts 48. Thus the coacting curved parts 47 and 48 form a relatively deep and wide saddle in which may be laid one side of a window drape. 60 It will be readily seen that since the two portions of the tongue of the drape supporting saddle are in slightly convergent relation, when the tongue is inserted into the slot 46 such portions will be forced together and thus a tight frictional 65 connection will be established between the saddle and the outer end of the arm portion or part 21.

A further novel feature and advantage of applicant's invention resides in the horizontal adjustability of the entire bracket in a direction 70 transversely of the window frame, by reason of the novel connection between the base plate and the foot plate 22 of the bracket arm. By reason of this horizontal adjustable connection between the base plate and the bracket arm foot plate it 75 will be seen that the job of mounting shade rollers

is greatly facilitated. With the standard type of shade roller supporting bracket where the arm and the plate which is secured to the frame are in one piece, it is necessary to make careful measurements so as to get the supporting brackets properly spaced apart to receive the shade roller. If such measurements are not accurate it is necessary that one or both of the brackets be removed and reset. In the present case the base plates 12 are set as accurately as possible 10 and then if more or less space is required between the bracket arms 10 to properly support the shade roller this can be acquired by shifting the arms so as to move the foot plates 22 toward or away from the sides of the window frame.

It will also be readily apparent that with the present invention, after the brackets have been properly set so that the shade rollers are properly mounted therebetween with the roller gudgeons engaged in the openings 36 of the auxiliary brackets 33, it is impossible for the shade roller to be accidentally displaced as is the case in connection with the use of those mounting brackets where one of the brackets is provided with an open slot in which a roller gudgeon is positioned. With the last named type of brackets the rapid or careless rolling up of the shade on the roller or the application of an upward force to the roller usually results in the roller jumping out of the brackets and falling. In the present case this cannot occur since the gudgeons at the ends of the roller are completely enclosed.

It will be readily apparent that this enclosing of the gudgeons on the ends of the roller is accomplished easily and quickly by first properly separating the arms 10 to permit the roller to be put into proper position and then moving the arms 10 together so as to introduce the gudgeons into the auxiliary bracket apertures.

A construction of the type described is of particular advantage and constitutes a safety feature especially where used in a nursery or some other room where there are children who might play with the shade and cause it to fall.

While in the illustration of the invention only a single extensible curtain bar 38 has been illustrated it is to be understood that a plurality of such bars may be readily mounted between a pair of arms 10 if desired. Where it may be desired to use more than one of the extensible bars 38, suitable space can be provided between the extensible bars by lengthening the arms 10 in the manner described.

From the foregoing it will be readily apparent that there is provided in the present invention a novel shade and curtain fixture in which the parts may be readily stamped from suitable sheet metal and wherein connections and adjustments between the parts may be easily and quickly made without the use of screws, bolts or other securing elements of a similar nature. At the same time there is produced a fixture which is strong and rigid and which will support a considerable weight without bending, twisting or in any way breaking down.

I claim:

1. In a shade and curtain fixture of the character described, a two-part extensible arm in which the parts are in juxtaposition, means for securing an end of one arm part to a fixed support, means coupling the parts to facilitate adjustable movement of the other arm part relative to the said one part for lengthening and shortening the arm, a curtain supporting rod, means for coupling an end of the rod with the

two arm parts, said coupling means forming a locking connection between the arm parts, and an auxiliary bracket supported on the inner side of the said one arm part and adapted to support an end of a shade roller.

5 2. A shade and curtain fixture of the character stated in claim 1, wherein the said means for coupling an end of the rod with the two arm parts, comprises a slot formed in the top edge of the said one arm part, a plurality of slots formed in the top edge of the said other arm part, one of said plurality of slots being positioned at the side of the first slot, and a slot formed in the bottom edge of the said end of the rod, the rod slot being engageable with the two adjacent slots of the arm parts.

15 3. A shade and curtain fixture of the character described in claim 1, in which the said auxiliary bracket is connected with the top and bottom edges of the said one arm part and projects laterally inwardly from the extensible arm.

20 4. A shade and curtain fixture of the character described, comprising a two-part extensible arm in which the parts are in the form of relatively long flat strips of material disposed in juxtaposition, means for securing an end of one arm part to a fixed support, the other end of the said one arm part having a laterally turned slotted flange through which the other arm part is slidably extended, an interlocking sliding connection between the inner end of the said other arm part and the said one arm part whereby the said other arm part is shiftable through the slotted flange with respect to the said one arm part, said shiftable arm part having a plurality of slots cut vertically therein from its top edge, the said one arm part having a single slot cut vertically therein from its top edge adjacent to said flange, the shiftable arm part having notches in its lower edge 25 30 35 40 45 50 55 60 65 70 75 engageable with the lower edge of the flange slot whereby any one of the slots formed in its top edge may be brought into side by side relation with the slot of the said one arm part, and an extensible two-part curtain rod in the form of a relatively long flat strip of material having a vertical slot cut in its bottom edge adjacent to each end, the slot at an end of the rod being adapted for interlocking engagement with the said adjacent slots of the two arm parts.

5. A shade and curtain fixture of the character described in claim 4, in which the said shiftable arm part has an additional slot cut vertically therein from the top edge and adjacent to its free end, and a drapery pole and drapery supporting unit having a slotted tongue designed for interlocking connection with the last mentioned slot of the said other arm for the support of the unit in vertical position at the outer end of said last named arm part.

6. In a shade and curtain fixture of the character described, a shade roller and curtain rod supporting arm, a foot plate at one end of and in a plane perpendicular to the arm, and mounting means for the arm comprising a base plate having a pair of spaced parallel outstruck guide flanges, the base plate between the guide flanges having a central cut out area leaving between each guide flange and the area a relatively narrow strip of material paralleling the guide flange, 70 the said narrow strip of material adjacent to each guide flange being outwardly bowed to form a spring member, and said foot plate having a vertical dimension to facilitate the slidable engagement of its top and bottom edges in said guides, 75 the foot plate when slidably engaged in the guides

having frictional contact with said outbowed strips.

7. A shade and curtain fixture of the character described, comprising a two-part extensible arm in which the parts are in the form of relatively long flat strips of material disposed in juxtaposition, means for securing an end of one arm part to a fixed support, means slidably coupling the arms together whereby the other arm part may be shifted longitudinally of the said one arm part for lengthening and shortening the arm, means for locking the shiftable arm part in an adjusted position on the said one arm part, a curtain rod, means for coupling an end of the curtain rod with the arm parts, a drapery supporting unit carried upon the outer end of the shiftable arm part, and a shade roller supporting bracket coupled to the top and bottom longitudinal edges of the said one arm part between the curtain supporting rod and the secured end of the said one arm part and extending inwardly from the arm.

8. In a shade and curtain fixture of the character stated, a relatively long arm, means for securing an end of said arm to a fixed support, said arm including a long flat strip of material, lugs integral with the top and bottom longitudinal edges of said strip of material and a shade roller supporting auxiliary bracket comprising a strip of flat material having divergently related side arms and a short straight intermediate connecting portion, said connecting portion having an opening for the reception of a gudgeon of a shade roller, the free ends of the diverging arms of the auxiliary bracket having slots each designed to receive a lug whereby said auxiliary bracket extends inwardly from the said fixed arm with the

said intermediate apertured portion in spaced parallel relation with the supporting arm.

9. In a shade and curtain fixture of the character described, a relatively long arm member 5 including a flat long strip of material, means for securing one end of the arm member to a fixed support, said flat strip of material having a vertical slot formed therein from the top edge, and a drapery supporting unit in the form of an upwardly opening substantially U-shaped saddle, said saddle having a bottom tongue portion having a vertical slot therein from its lower edge, the tongue portion being insertable in the first mentioned slot and the slot of the tongue portion receiving the lower part of the said flat strip of material.

10. A shade and curtain fixture of the character stated in claim 9, wherein said drapery supporting unit has the tongue portion thereof formed 15 as two connected upwardly diverging parts which are pressed together upon insertion into the first mentioned slot to establish a friction lock with the said strip of material.
